(57) **CLAIM**

The ornamental design for a fixing device for calibration target as shown and described.

DESCRIPTION

FIG. 1 is a first perspective view of a fixing device for calibration target showing our new design;

FIG. 2 is a second perspective view thereof;

FIG. 3 is a front view thereof;

FIG. 4 is a rear view thereof;

FIG. 5 is an enlarged left side view thereof;

FIG. 6 is an enlarged right side view thereof;

FIG. 7 is a top plan view thereof;

FIG. 8 is a bottom plan view thereof;

FIG. 9 is an enlarged view of a circled portion 9 of FIG. 1; and,

FIG. 10 is an enlarged view of a circled portion 10 of FIG. 2.

The broken lines depict portions of the fixing device for calibration target in which the design is embodied that form no part of the claimed design.
